US0D1059388S

(12) **United States Design Patent** (10) Patent No.: **US D1,059,388 S**
(45) Date of Patent: ** Jan. 28, 2025

(54) **DISPLAY SCREEN OR PORTION THEREOF WITH GRAPHICAL USER INTERFACE**

(71) Applicant: **MTD PRODUCTS INC**, Valley City, OH (US)

(72) Inventor: **Ryan Maibach**, Valley City, OH (US)

(73) Assignee: **MTD Products Inc**, Valley City, OH (US)

(**) Term: **15 Years**

(21) Appl. No.: **29/856,668**

(22) Filed: **Oct. 17, 2022**

(51) LOC (15) Cl. **14-04**

(52) U.S. Cl.

USPC **D14/486**

(58) **Field of Classification Search**

USPC **D14/485-495**

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
